UNITED STATES PATENT OFFICE.

WILLIAM BANWARTH, OF GARY, SOUTH DAKOTA.

AUTOMOBILE SPRING.

Application filed March 15, 1921. Serial No. 452,483.

To all whom it may concern:

Be it known that I, WILLIAM BANWARTH, a citizen of the United States of America, and resident of Gary, in the county of Deuel 5 and State of South Dakota, have invented certain new and useful Improvements in Automobile Springs, of which the following is a specification.

This invention relates to springs for Ford 10 automobiles and has for its object the provision of a novel spring and an arrangement for its attachment to Ford automobiles now in common use, by which the length of the spring as compared with those ordinarily 15 employed on Ford automobiles is increased and whereby the action of the spring is improved in that it increases the comfort of the occupant of the automobile.

It is a further object of this invention to 20 produce a spring of the character indicated which will operate as a shock absorber by reason of the presence of scroll formations at the ends of the springs at their junctions with the shackles by which the springs are 25 connected to the spring perches.

A still further object of this invention is to produce a spring having qualities indicated while at the same time it is strong and durable and the leaves thereof are held 30 in assembled relation to each other so as to prevent their dissociation.

With the foregoing and other objects in view, the invention consists in the details of construction, and in the arrangement and 35 combination of parts to be hereinafter more fully set forth and claimed.

In describing the invention in detail, reference will be had to the accompanying drawing forming part of this application 40 wherein like characters denote corresponding parts in the several views, and in which—

Figure 1 illustrates a front elevation of a spring applied to the front axle of a Ford automobile; and

Figure 2 illustrates a perspective view of a fragment of the said spring.

In these drawings I have shown the spring 5 as comprising eight leaves preferably connected together at their centers by a bolt 6 50 which holds them from creeping longitudinally, the said spring being employed in connection with clips 7 by which the spring is secured to the frame of the chassis.

It will be seen that the lower leaves and 55 preferably two of them are scroll form at each end, as shown at 8, and next to the

lower leaf terminates in an eye 9 at each end by which it is connected to the shackles 10 pivotally connected to the spring perches 11, which spring perches are of the ordinary 60 Ford type slightly differently situated in that the curved ends extend outwardly instead of inwardly as they do when operating in conjunction with the ordinary type of 65 Ford springs. In this form of the invention, the lowermost leaf reinforces the scroll at either end and it results in strengthening the structure without materially interfering with the spring action of the leaves.

It is furthermore shown that the formation of the scroll results in the production of a clearance between the lowermost leaf and the spring perches, a condition which permits movement of the spring without liability of its abutting the spring perches 75 unless the load is abnormal.

It has been found that a spring made in accordance with this invention can be readily applied to Ford automobiles now in common use by the simple expedient of an adjustment of the spring perches in the manner indicated, so that the conversion can be expeditiously accomplished without supplying any new parts except the spring itself. 80

I claim:

1. In a spring for Ford automobiles, a plurality of superimposed leaves connected together at their centers, the next to the last leaf having scroll form terminating under the spring, the lowermost leaf having its 90 end shaped to the configuration of the scroll, and means for attaching the spring to spring shackles.

2. In a spring for Ford automobiles, spring perches having outwardly curved 95 ends, a spring having its end terminating in a scroll bent under the spring, the said spring comprising a plurality of leaves next to the lowermost of which has the scroll formation for attachment to a scroll and 100 the lowermost of said leaves being shaped to the configuration of the scroll and reinforcing the same, and means for holding the leaves in assembled relation to each other.

3. The combination with an axle having 105 two rigid posts, of a leaf spring, the major leaf of which is provided at its ends with return bends extended beyond the posts, and links connecting the return bends to the posts.

4. The combination with an axle having 110 two upright rigid posts, the upper ends of

which are outwardly offset in opposite directions, of a leaf spring, the major leaf of which is provided at its ends with downwardly extended return bends extended beyond the posts, and links connecting the return bends to the posts.

5. A spring structure having in combination an axle having an upright rigid post adjacent each end thereof, the upper 10 ends of said posts being curved outwardly

toward the ends of said axle, a leaf spring secured to the body of a vehicle disposed above said axle and extending longitudinally thereof, said spring being curved downwardly toward said axle and having 15 the ends thereof provided with downwardly extending return bends extended beyond the posts, and links connecting the return bends to the posts.

WILLIAM BANWARTH.
